UNITED STATES PATENT OFFICE

HERMAN D. HINTERNESCH, OF BALTIMORE, MARYLAND

EAR TRUMPET

Application filed May 17, 1929. Serial No. 363,915.

The present invention relates to devices for aiding a person's hearing, commonly known as ear trumpets and comprises essentially a casing adapted to fit upon the ear of the person having intake and discharge ends and providing air passages within the casing between said intake and discharge ends for condensing the sound waves passing therethrough before the same enters the ear orifice.

The invention also embodies means for placing the casing upon the ear with facility and for securely retaining the casing in position thereon against accidental displacement.

One of the important objects of the invention is to provide a device of this character of a simple and practical construction, which is neat and attractive in appearance, which serves to efficiently amplify the air waves for discharge into the ear orifice of a person using the device, which is relatively inexpensive to manufacture and otherwise well adapted for the purpose for which the same is intended.

Other objects and advantages reside in the special construction, combination and arrangement of the various elements forming the invention as more fully hereinafter described and claimed, reference being had to the accompanying drawings forming part hereof wherein like numerals refer to like parts throughout, and in which:

Figure 1 is a side elevational view showing the device in position upon a person's head,

Figure 2 is a longitudinal sectional view therethrough,

Figure 3 is a sectional view with the outer plate of the casing removed and showing the tapering centripetal air passage therein,

Figure 4 is a rear elevational view,

Figure 5 is a front elevational view illustrating the manner in which the air discharge nipple fits snugly within the ear orifice,

Figure 6 is a fragmentary perspective view of the centripetal air passage mounted within the casing, and

Figure 7 is a rear elevational view of the device in position for use.

Referring now to the drawings in detail, for the purpose of illustration I have dis-

closed my invention as comprising a substantially flat casing 5, composed of inner and outer wall sections 6 and 7 respectively with one end of the casing open and with its opposite end curved as shown at 8.

The parts comprising the casing may be constructed of any suitable material well known in the art and secured in assembled position in any convenient and desirable manner to facilitate its manufacture in quantities.

Within the casing is positioned an air chamber 9 of generally centripetal formation, as will be more clearly observed from an inspection of Figures 3 and 6 of the drawings, and which includes a convolute wall 10 having one end indicated at 11 spaced from the curved wall 8 of the casing and with its opposite end 12 curled inwardly and terminating at a discharge opening 13 formed in the inner wall 6.

The inner wall 6 serves to close one side of the air chamber and the opposite side of said chamber, adjacent the outer wall 7, is provided with a tapered cover 14 inclining inwardly from the outer to the inner end of the convolute wall 10 and also inclined toward the center of the air chamber, as will be observed from an inspection of Figure 2 of the drawings.

The air chamber 9 opens toward one side of the casing, as indicated at 15 and extending outwardly from the center of said opening is a guide partition 16 which has its ends flared outwardly from said opening and terminating in spaced relation against the side wall of the casing.

The opposite edges of the partition 16 engage the inner side of the inner and outer sections 6 and 7 so as to close communication through that side of the casing provided with the partition. Consequently one section of the partition, indicated at 17 constitutes a guide for the air passage 18 formed between the rear curved wall 8 of the casing and the convolute wall of the air chamber for directing sound waves passing along said air passage to the opening 15 of the chamber 9.

Likewise the other section of said partition, indicated at 19 will serve to guide the sound waves entering the casing, from its

open end for directing the same also into the opening 15 of the air chamber so that the sound waves from the opposite sides of the casing will converge at the opening and enter the air chamber without interference 5 from each other.

At the side of the air chamber 9 nearest the open side of the casing is positioned a partition 20 having sides 20 and 21 diverging inwardly from the mouth end of the casing and forming individual air compartments A and B therein.

The sides 21 and 22 of the partition cooperate with the side walls of the casing to 15 gradually reduce the width of the compartment inwardly of the open end of the casing.

The inner end of the compartment A merges into the air passage 18 and the inner end of the compartment B is further reduced by the partition wall 19 and serves to direct air currents entering the compartment B directly into the opening 15 of the air chamber 9 for movement through said 25 chamber in the same direction as the air currents entering the chamber from the passage 18. It will thus be seen that the sound waves are gradually compressed before reaching the air chamber 9.

30 The discharge port 13 is removably secured to a tubular extension 23 of curved formation having a rubber nipple 24 fitted to its outer end and provided with a reduced discharge opening 25. The tubular extension 23 is adjustably arranged so that the nipple 24 may be properly positioned within the orifice of the ear 26 in a snug manner so that the sound waves after entering the orifice cannot escape around the sides of the 40 nipple.

To the outer surface of the inner casing section 6 is secured a pair of staples 27 under which a section of a bent wire 28 is inserted having its ends extending toward one 45 side of the casing with one of said ends curved as shown at 29 for extending over and behind the ear 26 whereby to secure the casing in position thereon.

The other end of the wire is formed into 50 a hook 30 adapted to engage the temple bar of a pair of eye glasses, which may be worn by the person, to further assist in retaining the casing in position upon the ear.

If desired a head band 31 may also be employed and constructed of a substantially thin flat strip adapted to be inserted under the staples 27 in friction gripping relation with the outer surface of the casing and in this manner the casing will be held against 60 displacement upon the ear.

It will be obvious from the foregoing that the sound waves entering the open end of the casing will be directed into the air chamber by means of the partition 16 and by reason 65 of the centripetal construction of the air

chamber the sound waves will be condensed before discharge from the casing to the tubular extension 23 after which the sound waves will be further condensed by reason of the reduced opening 25 in the nipple before entering the orifice of the ear. 70

In this manner the sound waves will be greatly amplified.

It is obvious that my invention is susceptible to various changes and modifications in construction without departing from the spirit of the invention or the scope of the appended claims, and I accordingly claim all such forms of the device to which I am entitled. 75

Having thus described my invention, what I claim as new is:

1. An ear trumpet of the class described comprising a casing open at one end, said casing having its end remote from the opening curved, a centripetal air chamber arranged within the casing with one end opening into the casing and with one of its walls disposed in spaced relation from the curved end of said casing to form an air passage communicating with the open end of the chamber, a partition arranged within the casing for directing sound waves from said air passage into the opening of the air chamber, said casing having a discharge port formed therein and communicating with the center of said air chamber, a tubular extension attached to said discharge port and a rubber nipple carried at the end of said extension for snugly fitting within the ear orifice, said nipple having a reduced opening at its discharge end. 90

2. An ear trumpet of the class described comprising a casing open at one end, said casing having its end remote from the opening curved, a centripetal air chamber arranged within the casing with one end opening into the casing and with one of its walls disposed in spaced relation from the curved end of said casing to form an air passage communicating with the open end of the air chamber, a partition arranged within the casing for directing sound waves from said air passage into the opening of the air chamber, said casing having a discharge port formed therein and communicating with the center of said air chamber, a tubular extension curved longitudinally with one end attached to said discharge opening and adapted for rotary adjustment with respect thereto and a rubber nipple attached to the outer end of said extension having a restricted opening at its discharge end. 105

3. An ear trumpet comprising a casing open at one end and having its opposite end curved, a centripetal air chamber arranged within the casing having one end opening into the casing and with its wall adjacent said open end disposed in spaced relation with the curved end of the casing whereby to form 110

an air passage therebetween, said air chamber having one of its sides tapering toward its center, guide means within the casing for directing sound waves from opposite sides of the air chamber into the open end thereof in a uniform direction, a discharge opening formed in the casing and communicating with the center of said air chamber and a reduced nipple connected to said discharge port adapted for snugly fitting within the ear orifice.

4. An ear trumpet comprising a casing open at one end and having its opposite end curved, guide means arranged within the casing adjacent its open end and including a pair of diverging sections cooperating with the walls of the casing to provide individual air compartments therein, a centripetal air chamber arranged within the casing at the inner ends of said guide means, said air chamber having one end opening into the casing, said air chamber including a convolute wall disposed in spaced relation from the curved end of the casing and also including a wall at right angles to said convolute wall and tapering toward the center of said air chamber, a partition disposed adjacent the open end of said air chamber for directing sound waves from said air compartments into the air chamber for travelling therethrough in a uniform direction, said casing having a discharge opening therein, a nipple adjustably connected to said opening to snugly fit within the orifice of the ear and means carried by the casing for attaching the same to the ear.

5. An ear trumpet comprising a casing having a mouth end, a plurality of air compartments formed within the casing, each having communication with said mouth end and tapering inwardly from the mouth end, a tapering centripetal air passage communicating at its larger end with the reduced portions of said compartment and a discharge port for said air passage.

6. An ear trumpet comprising a casing having a mouth end, a plurality of air compartments formed within the casing, each having communication with said mouth end and tapering inwardly from the mouth end, a tapering centripetal air passage communicating at its larger end with the reduced portions of said compartment, a discharge port for said air passage and a nipple revolvably attached to said discharge port and adapted for fitting in an ear orifice.

7. An ear trumpet comprising a casing having a mouth end, a plurality of air compartments formed within the casing, each having communication with said mouth end and tapering inwardly from the mouth end, a tapering centripetal air passage communicating at its larger end with the reduced portions of said compartment, a discharge port for said air passage and a nipple revolu-

bly attached to said discharge port and adapted for fitting in an ear orifice, said nipple having a restricted discharge opening.

8. An ear trumpet comprising a casing having a mouth end, a plurality of air compartments formed within the casing, each having communication with said mouth end and tapering inwardly from the mouth end, a tapering centripetal air passage communicating at its larger end with the reduced portions of said compartment, a discharge port for said air passage, a nipple revolvably attached to said discharge port and provided with a restricted discharge opening and a flexible beading formed on the sides of the nipple inwardly of the discharge opening to provide an air tight seal with the walls of the ear orifice within which the nipple is inserted.

9. An ear trumpet comprising a casing having a mouth end, a plurality of air compartments formed within the casing, each having communication with said mouth end and tapering inwardly from the mouth end, a tapering centripetal air passage communicating at its larger end with the reduced portions of said compartment, a discharge port for said air passage, a nipple revolvably attached to said discharge port and provided with a restricted discharge opening, a flexible beading formed on the sides of the nipple inwardly of the discharge opening to provide an air tight seal with the walls of the ear orifice within which the nipple is inserted and means for attaching the casing to the ear comprising a wire hanger having one end bent for fixing over and behind the lobe of the ear and with an intermediate portion of the wire formed with a return bend to provide a pair of parallel sections and staples carried by the casing for receiving said sections of the wire and retaining the same in spring pressed engagement.

10. An ear trumpet comprising a casing having a mouth end, a plurality of air compartments formed within the casing, each having communication with said mouth end and tapering inwardly from the mouth end, a tapering centripetal air passage communicating at its larger end with the reduced portions of said compartment, a discharge port for said air passage, a nipple revolvably attached to said discharge port and provided with a restricted discharge opening, a flexible bearing formed on the sides of the nipple inwardly of the discharge opening to provide an air tight seal with the walls of the ear orifice within which the nipple is inserted and means for attaching the casing to the ear comprising a wire hanger having one end bent for fitting over and behind the lobe of the ear and with an intermediate portion of the wire formed with a return bend to provide a pair of parallel sections, staples carried by the casing for receiving said sections of the

wire and receiving the same in spring pressed engagement and a hook formed on the opposite end of the wire for detachably securing the wire to the temple bar of a pair of eye glasses.

5 11. An ear trumpet comprising a casing having a mouth end, a plurality of air compartments formed within the casing, each having communication with said mouth end and tapering inwardly from the mouth end, a tapering centripetal air passage communicating at its larger end with the reduced portions of said compartment, a discharge port for said air passage, a nipple revolvably attached to said discharge port and provided with a restricted discharge opening, a flexible bearing forming on the sides of the nipple inwardly of the discharge opening to provide an air tight seal with the walls of the ear orifice within which the nipple is inserted, and means for interchangeably attaching the casing to either ear comprising a wire hanger having one end bent for fitting over and behind the lobe of the ear and with an intermediate portion of the wire formed with a return bend to provide a pair of parallel sections, staples carried by the casing for receiving said sections of the wire and retaining the same in spring pressed engagement

20 and a hook formed on the opposite end of the wire for detachably securing the wire to the temple bar of a pair of eyeglasses.

12. An ear trumpet comprising a casing having a mouth end, a plurality of air compartments formed within the casing, each having communication with said mouth end and tapering inwardly from the mouth end, a tapering centripetal air passage communicating at its larger end with the reduced portions of said compartment, a discharge port for said air passage, a nipple revolvably attached to said discharge port and provided with a restricted discharge opening, a flexible bearing forming on the sides of the nipple inwardly of the discharge opening to provide an air tight seal with the walls of the ear orifice within which the nipple is inserted, and means for interchangeably attaching the casing to either ear comprising a wire hanger having one end bent for fitting over and behind the lobe of the ear and with an intermediate portion of the wire formed with a return bend to provide a pair of parallel sections, staples carried by the casing for receiving said sections of the wire and retaining the same in spring pressed engagement, a hook formed on the opposite end of the wire for detachably securing the wire to the temple bar of a pair of eyeglasses and a head band

55 having one end removably inserted under said staple between the parallel sections of the wire and with its opposite end adapted to extend across the top of the head of the wearer.

In testimony whereof I affix my signature.
65 HERMAN D. HINTERNESCH.
